CLAIM

The ornamental design for a sterilizer, as shown and described.

DESCRIPTION

FIG. 1 is a front-bottom perspective view of a sterilizer of the present disclosure;

FIG. 2 is a rear-top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings are for the purpose of illustrating portions of the sterilizer and form no part of the claimed design.
